HAIR TRIMMER

Harrison Lewis, San Francisco, Calif.

Application August 31, 1937, Serial No. 161,777

2 Claims. (Cl. 30—90)

The invention, in general, relates to blade and comb combinations for simultaneously combing and trimming hair and more particularly relates to a device to which practically any of the commercial types of safety razors may readily be attached for the hair trimming operation.

A primary object of my invention is to provide a device of the aforementioned nature which is characterized by its ability to effect smooth and symmetrical trimming and thinning of the hair, eyebrows, burn-sides, mustache or beard and which, particularly in the trimming of the hair, does not leave the hair in a so-called "step" or ragged condition.

Another important object of my invention is to provide a compact hair trimming device to which safety razors of almost any type or design may be attached in various desired angular relationships thereby affording a wide range of adjustability between blade and comb for trimming the hair to any desired length.

Another object of the invention is to provide a hair trimmer of the aforementioned character which can be used effectively, rapidly and skillfully by even inexperienced persons without likelihood of injury to the scalp or face.

A still further object of my invention is to provide an efficient hair trimmer which can be constructed relatively inexpensively and which has a minimum of parts for assembly.

Other objects of the invention together with many of its advantageous features will appear from the following description of a preferred and one modified embodiment of my invention illustrated in the accompanying drawing.

While I have shown a preferred embodiment of the invention, together with a modification thereof, in the accompanying drawing, it is to be understood that I am not to be limited to the embodiments illustrated, as my invention, as defined in the appended claims, can be embodied in a plurality and variety of forms.

Referring to the drawing:

Figure 1 is a perspective view of a preferred embodiment of my invention.

Figure 2 is an elevational view, partly in section, illustrating the attachment of a convex base type of safety razor to the preferred embodiment of my invention.

Figure 3 is a perspective view of a modified embodiment of the invention.

Figure 4 is an elevational view, partly in section, illustrating the attachment of a straight back safety razor to the preferred embodiment of my invention.

In its preferred form, the hair trimmer of my invention preferably comprises a body having a substantially flat bottom, an arcuate end, and an upper surface which includes a comb with relatively long, uniformly spaced teeth merging into a concave portion which, in turn, merges into a straight slanting portion, together with a pair of lugs integral with the sides of the body and overlying its upper surface, said lugs being provided with threaded apertures for the reception of thumb-screws thus enabling safety razors of practically any design of head to be adjustably attached to the body for various angular relationships between the comb of the body and the blade of the razor thereby affording trimming of the hair to any desired length.

As illustrated in Figures 1 and 2 of the drawing, I preferably provide a body 11 which may be molded or cast from any suitable metal, such as brass, and which preferably includes a substantially flat bottom 12 and an arcuate or rounded end 13. The body 11 preferably is provided with an upper surface which terminates at one longitudinal extremity in a comb 14 and I preferably construct the comb portion of the device with a plurality of relatively long, uniformly spaced teeth 16 terminating in rounded points 17. The upper surface of the body 11 preferably is divided into two main portions of which a concave portion 18 occupies the major part of the surface. As illustrated, the concave portion 18 merges at one longitudinal extremity with the comb 14 and at its other longitudinal extremity with a straight but slanting portion 19, the latter terminating at the rounded end 13 of the body. Preferably, the entire upper surface of the body 11, exclusive of the teeth of the comb 14, is knurled, as at 21, to prevent likelihood of slippage between the head or cap of the razor and the body when the two are assembled.

In accordance with the invention, the body 11 is provided with a pair of lugs 22 which are formed integrally with the body 11 and conveniently extend from opposite sides of the body and are bent to overlie the upper surface of the body. Each of the lugs 22 is provided with a threaded aperture 23 for the reception of a small thumbscrew 24 to enable the attachment of a safety razor 26 to the body 11, as illustrated particularly in Figure 2 of the drawing. The location of lugs 22 on the body 11 is not critical for these elements serve only to enable the attachment of a razor to the body and, hence, can

be positioned at any suitable points on the body 11 for effecting this function.

In Figure 2 of the drawing, I have illustrated the attachment of a common type of presently marketed safety razor to the body 11, such razor incorporating a base or cap section 27 for the blade 28 which is convex on its outer surface. As shown, the convex outer surface of the base or cap 27 of the razor 26 fits snugly upon the concave portion 18 of the body 11 of my device. In the position of the razor with respect to the body 11 illustrated, the relationship between the comb 14 of the body and the blade 28 is such that the teeth 16 of the comb project an appreciable distance beyond the guard 29 of the razor and, in this relationship, relatively long lengths of hair may be trimmed. It is apparent that the razor 26 may be shifted with respect to the body 11 so that the handle 31 of the razor assumes a differently inclined position with respect to the body 11 than that shown and in so shifting the razor, the convex surface of cap 27 may be moved forwardly toward the comb 14 or rearwardly toward the inclined portion 19 of the upper surface of body 11 thus variably adjusting the razor to the body 11 for long, medium or short trimming of the hair. This variable adjustment affords trimming of the hair of the scalp or trimming of burn-sides, eyebrows, mustache or beard to the desired degree and only requires a moment for the adjustment. Of course, after setting the razor in the desired position on the body 11 it requires only a turning of the thumb-screws 24 to engage the same firmly to the normally lower side of the guard 29 of the razor and thus attach the razor firmly to the body.

In Figure 4 of the drawing, I have illustrated the attachment of another type of conventional safety razor to the preferred embodiment of the invention, such type of razor incorporating a straight back or cap section. As shown, the outer surface of the straight back of the base 27 of this type of razor is brought into engagement with the straight but slanting portion 19 of the body 11 of my device. As with a razor having a convex base and illustrated in Figure 2 of the drawing, the straight back razor 26 may be shifted on the slanting portion 19 of the device 50 so that the guard 29, blade 28 and handle 31 thereof will assume differently inclined positions with respect to the body 11. This shifting of the razor may be forwardly toward the comb 14 of the device or rearwardly toward the arcuate end 13 of the body. Moreover, if desired, the razor 26 can be positioned on the slanting portion 19 of the device so that the leading edge of the blade 28 will be at an angle with respect to a transverse line through the comb 14 and thereby enhance the cutting quality for some sections of the head. Thus, the conventional safety razor of the straight back type, as illustrated in Figure 4 of the drawing in position on the device, can be variously adjusted with respect to the body 11 for long, medium or short trimming of the hair in the same manner as the convex base type of razor can be adjusted. While I have omitted showing the lugs 22 and thumb-screws 24 from the illustration of Figure 4 of the drawing, it is to be understood that these parts function with the straight back type of safety razor in the same manner as with the other types, see Figure 2 of the drawing, to hold the razor firmly attached to the body 11 in the desired position.

A modified embodiment of my invention is illustrated in Figure 3 of the drawing. In this modification, which likewise can be molded or cast as a unit from any suitable metal, such as brass, I provide a body 111 having a substantially straight lower surface 112, a straight end 113 and an upper surface provided at one longitudinal extremity with a comb 114. The comb 114 may be the same as the comb 14 of the embodiment shown in Figure 1 of the drawing and shall include a plurality of uniformly spaced, relatively long teeth 116 terminating in rounded points 117. The upper surface of this modification of the invention preferably is entirely concave in contour, the concave portion 118 extending from the comb 114 to the end 113 of the body. Preferably, the juncture between the concave portion 118 of the upper surface and the end 113 of the body is rounded, as at 119. As illustrated, the concave upper surface 118 of body 111 is knurled, as at 121, so that the possibility of slippage between the body and the razor to be attached to the body will be reduced to a minimum. In this modification, I also provide a pair of lugs 122 on opposite sides of the body 111 and these lugs may be formed integral with the body in its manufacture. Each lug is bent inwardly, as shown, to overlie the upper surface of the body and each lug conveniently is provided with a threaded aperture 123 for the reception of a thumb-screw 124 which, when screwed down toward the surface 118 will engage the lower side of the guard of a safety razor and firmly attach the razor to the body 111. This modification is designed primarily for use in conjunction with safety razors having a base or cap section for the blade with a convex outer surface which, of course, is complementary to the concave portion 118 of the upper surface of the body. Hence, the safety razor of the type 40 mentioned can be readily and adjustably attached to the body 111 for various angular relationships between the comb 114 and the blade of the razor to effect long, short or medium trimming of the hair.

It is clear from the foregoing as well as the views illustrated in the accompanying drawing that I have provided a practical, compact device having a combined slanting and concave surface for affording the attachment and close fitting thereto of safety razors of various designs or types having either a flat or convex base or cap section. Such safety razors may be held firmly in place upon the body or device in any desired angular relationship so that the trimming of the hair may be effected easily and with optimum results as regards smoothness and symmetry and freedom from "stepping" or ragged ends. Moreover, that such device can be rapidly used by anyone regardless of prior experience in hair trimming without likelihood of any injury whatsoever. The device is especially useful for those in military or naval service where it often occurs that a fresh, neat appearance must be had on extremely short notice. The attachment of the safety razor to the device of my invention is a matter of only a few seconds and the hair, beard or burn-sides trimming requires but a few minutes. The device has exceptional value to those shut-in in hospitals, sanitoriums and the like where access to barber shops is burdensome, if not impossible. In addition to the foregoing uses for individuals, it also is apparent that the device, with safety razor attached, may readily

be employed to trim or thin-out the hair of animals with safety to the animal.

5 Due to the fact that the device or body can be molded or cast as a unit, with the exception of the small thumb-screws, the manufacturing cost of the body is materially lessened. Moreover, the device has a minimum of parts for assembly and for attaching a razor thereto, hence the possibility of losses of necessary equipment

10 is reduced materially.

It is to be understood that the appended claims are to be accorded a range of equivalents commensurate in scope with the advance made over the prior art.

15 I claim:

1. A new article of manufacture to which a safety razor may be adjustably attached for trimming the hair to any desired length, said article comprising a body, a substantially flat bottom 20 on said body, a concave surface on said body for cooperative adjustable engagement with the convex surface of a safety razor base, a comb merging with and extending from one longitudinal extremity of said concave surface, a flat

surface contiguous to and extending from the other longitudinal extremity of said concave surface; said flat surface being inclined relative to said flat bottom and being adapted to be adjustably engaged by a flat surface of a safety 5 razor base, and means on said body for adjustably attaching a razor to said body.

2. A device for use in trimming the hair and to which a conventional safety razor may be attached, said device consisting of a body having 10 a surface with a concave portion and a flat portion contiguous to said concave portion; said flat surface being inclined with respect to said concave portion, comb teeth on said body extending from said concave portion of said surface, and 15 a lug on said body having a threaded aperture therein through which a screw may be threaded to engage the base of a safety razor and thereby enable adjustable attachment of the safety razor to the body in any selected one of a plurality of angular or curved positions for trimming the hair short or long as desired. 20

HARRISON LEWIS.
